APPARATUS FOR HOISTING LIQUIDS FROM WELLS.

1,077,088

Specification of Letters Patent. Patented Oct. 28, 1913.

Application filed September 10, 1912. Serial No. 719,563.

To all whom it may concern:

Be it known that I, DUNCAN D. McCALL, a citizen of the United States, and a resident of Houston, in the county of Harris and State of Texas, have invented a new and Improved Apparatus for Hoisting Liquids from Wells, of which the following is a full, clear, and exact description.

This invention relates to apparatus for raising liquid from wells by means of a compressed fluid, such as air or other vapors or gas, and has reference more particularly to the class comprising a member carrying a compressed fluid, a member used as a cylinder for the liquid to be hoisted, and a member conveying said liquid to a desired place, together with means associated with the above members whereby the flow may be controlled.

An object of the invention is to provide an inexpensive apparatus, simple and durable in construction, which has few moving parts, their motion and nature being such as not to wear them or require any special attention.

Another object of the invention is to provide an apparatus that will leave the liquid in the well always under normal pressure while hoisted or pumped by the compressed fluid.

A further object of the invention is to provide an apparatus in which the amount of the liquid to be hoisted may be varied from full capacity to any desired fraction of the capacity of the apparatus.

It is a well known fact that in wells where the hoisting of liquid is performed by a compressed fluid, and in which the compressed fluid has direct contact with the liquid in the well, the supply of liquid in such wells is rapidly diminished, and it is explained by the fact that the fluid pressure forces the liquid back to the supply veins or checks their supply by said veins. To obviate this and maintain the supply normal I have invented the apparatus hereinafter described.

Reference is to be had to the accompanying drawings forming a part of this specification, in which like characters of reference indicate corresponding parts in all the views, and in which—

Figure 1 is an elevation of an embodiment of my invention, showing its operative position in a well; Fig. 2 is a vertical central section through same at the head of

the well; Fig. 3 is a similar section showing the connection and operative position of fluid and liquid conduits, the cylinder and check valve; Fig. 4 is also a similar section showing the structure at the foot of the well and the position of the check valve; Fig. 5 is a side elevation showing the connection of the fluid conduits from compressor to the head of the apparatus, and the means for operating the fluid admission and exhaust from said head; Fig. 6 is a vertical section through the valve for the admission and exhaust of fluid; Fig. 7 is a plan view of the same for operating the above stated well; and Figs. 8 and 9 show a modified form of my apparatus.

Before proceeding to a more detailed description of my invention it must be understood that the compressed fluid may operate a series of wells each provided with my apparatus, and a central pressure reservoir may be introduced between the pressure carrying line and the outlet of the compressor cylinder for a more uniform flow and pressure in the line and in the apparatus.

Referring to the drawings, 10 is a fluid compressor, preferably air, and 11 is a tank from which the compressor draws the air by means of pipes 10'. The pressure of air in the tank 11 is below atmospheric and is regulated by the tension of a spring 12 placed on the stem 13 of an admission valve operated through the valve casing 14. A conduit 15 connects the admission tank 11 with the T-member 16 of the fluid valve casing 17, and the casing 17 has a conduit 18 connecting same with the outlet of the compressor. The casing 17, as best seen in Fig. 6, has a vertical through bore 19 and a horizontal cylindrical bore 20 reduced at the end opposite the connection 18 so as to guide the cylindrical piston rod 21 of the cylindrical valve 22 positioned in the bore 20. The cylindrical valve 22 at the end opposite the rod 21 is provided with a central axial bore 23 having an opening 24 on the cylindrical surface of the valve, and is adapted to register with the vertical bore 19 in the lower end of the valve casing 17 only. Through this bore 23 air is forced into the apparatus from the compressor. A through bore 25 normal to the axis of the cylindrical casing 17 and in the same plane with the opening 24 is provided in the said valve. The bore 25 is adapted to register with the bore 19 above and below in the valve casing 17, and

through this bore the fluid pressure in the apparatus is reduced to the desired amount by means of the admission valve in the tank 11. A body portion is left between the two bores 23 and 25, and it is provided with a piston ring to prevent leakage between said bores and the bore 20 of the casing 17. For the same reason a stuffing box is provided at the end of the valve casing 17 where the piston rod 21 projects. The rod 21 is provided with a yoke 26 adapted to slide only, and provided with two surfaces 27-28 adapted to engage projections or lugs 29 and 30 respectively, placed on the respective faces of the disk 31. The disk 31 is provided with a shaft 32 driven at the desired speed and in any desired manner. The lug 29 is integral with one of the faces of the disk 31, while the lug 30 is fixed to the opposite face of the disk by means of a bolt 33. A slot 34 is also provided in the lug 30, and a series of holes 35 in the disk 31 for the bolt 33, so that the lug 30 can be advanced or retarded with reference to the fixed lug 29. The purpose of this will appear hereinafter. It is easily seen that by the rotation of the disk 31 the yoke 26 is alternately translated in one or the other direction, and, in consequence, the piston valve 22 is similarly translated, and therefore alternate communication between the lower part of the bore 19 in the casing 17 is established, with the opening 24 of the bore 23 and with the bore 25, both of the valve 22. The purpose of this will be explained later in the description.

A check valve casing 36 is provided above the exhaust and T-member 16, having a valve 37 so disposed that when the fluid pressure is cut off from the apparatus the pressure in the apparatus cannot be higher than the atmospheric pressure. The lower part of the bore 19 of the valve casing 17 is connected with the pipe line 38 (see Figs. 2 and 3) extending a little above the natural level of the liquid in the well, and at its lower end being provided with a T-member 39 so as to baffle the flow of the compressed fluid on the liquid. On both the T-member 39 and pipe 38 a head 40 is mounted, concentric with the line, and carrying a cylinder 41 at its lower end, so that it may be said that this cylinder is suspended on the head 40 attached to the line 38. Inclosing the cylinder 41, and having a predetermined clearance 42 between them and concentric with the said cylinder 41 is a cylindrical shell 43, all practically the same length and having their upper and lower edges at nearly the same level. The lower end of the shell 43 is provided with a reduction 44 carrying a nipple 45 of the same internal diameter as the cylinder 41. A check valve 46 is attached to the nipple so as to admit the liquid only inwardly and check its out-

flow through the said nipple. The upper end of the shell 43 is also provided with a reduction 47 carrying a nipple 48 similar to the nipple 45, and a check valve casing 49. The reduction 47 is attached to the head 40 by means of rivets 50, and by means of these rivets, and others below (not shown in the drawings) the cylinder 41 and shell 43 are maintained concentric to each other. The check valve casing 49 is provided with a valve 51 having a regular seat 52 and an additional support 53 provided in the spider member 54 positioned in the lower part of the casing. The additional support helps the valve 51 to withstand the hydrostatic head when the apparatus is in action, as the valve is so positioned as to allow the liquid to pass up only. The valve 51, as can be seen from Fig. 3, is mounted on the pipe line 38 and uses the same as a stem for its guidance.

To the upper end of the check valve casing 49 a pipe line 55 is connected which projects through the top 56 of the well casing 58 and is concentric with the line 38 and provided with a T-member 57 which rests on the top 56 and supports the entire apparatus freely and loosely in the well casing 58. The T-member 57 is provided with an outlet for liquid 59, and a stuffing box 60 through which the line 38 projects, the purpose of said box being to eliminate leakage between the air line and the T-member 57. The outlet or discharge 59 is provided with a check valve 61 so as to diminish the hydrostatic head on the check valve 51.

In the modified form of my apparatus the air line 38' is connected to the head 40' of cylinder 41' similarly as in the above described construction. A member 62 is attached to the lower end of the cylinder 41' and is provided with a nipple 45' and check valve 46' at the lower end, and with a nipple 63 and check valve casing 49' at the upper end and parallel to the cylinder 41'. The check valve casing 49' is provided with a pipe line 55' forming the conduit for the liquid to be hoisted. The upper part of the well casing is similar to that above described, only having different means for suspending the apparatus in the casing. This modified construction may preferably be used in wells of larger diameters.

The compressed air of the running compressor is continually applied in the conduit 18 and maintained in same at a desired pressure by means of a safety pressure valve 18'. Through the medium of the rotating disk 31 the lug 30 displaces the lug 26, and thereby the cylindrical valve 22 is placed as shown in Fig. 6; then the compressed air from the conduit 18 through the bore 20 of the valve casing 17 is conveyed to the bore 23, to the surface opening 24 of the cylindrical valve 22 and lower part of the ver-

tical bore 19, into the air line 38, and finds its escape through the T-member 39 at the foot of the air line and at the top of the cylinder 41. The water level in the cylinder 41 before the pressure is applied in the same (or at atmospheric pressure) is of the same level as it is in the well casing, and the same level of water is in the space between the shell 43 and the cylinder 41. The compressed air forced through the air line 38 forms a piston in the cylinder 41 and forces the liquid out of the said cylinder through the reduction 44, thus seating the check valve 46 and forcing the liquid through the clearance 42 formed by the cylinder 41 and the shell 43 and through the check valve 51 and out of the well.

When the apparatus is running to its full capacity the motion of the piston slide valve 22 is so arranged that the yoke 26 is returned by the lug 29 of the flange 31 to the original position from which it was displaced by the lug 30 in the same interval of time as it requires to compress air to force the liquid from its upper level in the cylinder 41 to its lower extremity. When this takes place the compressed air is cut off from the air line 38, and the bore 25 of the cylindrical slide valve 22 registers with the air line, but the pressure in the line being higher than the atmospheric will rapidly rush into the intake tank 11 of the compressor through the conduit 15 and fill same until its pressure is equal to the atmospheric, and if the pressure in the line is still above the atmospheric it will find its escape through the check valve 37 placed above the T-member 16 on the valve casing 17. As the compressor continues to take the air from the intake tank 11 and sends it to the conduit 18, the pressure in said tank, as above stated, being regulated by the tension of the spring 12, it is always below atmospheric, therefore, the pressure in the air line 38 and cylinder 41 will fall below the atmospheric also. The liquid in the pipe line 55 and passage 42 is checked from backing by the check valve 51, and the hydrostatic head being constant in the well forces the liquid into the cylinder 41 through the check valve 46 at its foot to the level in the well, and even higher, as the pressure in the line is below atmospheric, as above stated. At this moment, when the water reaches its higher level in the cylinder 41, the cylindrical slide valve 22 again admits the compressed air through the air line, as above described, and another cycle takes place.

It can be seen from the drawings that by the displacement of the lug 30 on the disk 31 the time of opening and closing the slide valve 22 is varied so that the compressed air is only applied during such an interval of time as to give the desired fractional part of the volume of water to cylinder 41, when

the exhaust is opened as above described. Therefore the hydrostatic head of the well will force the fallen level of water into the cylinder 41 up to balance the reduced pressure produced by the suction of the compressor and regulated by the tension of the spring 12 into the admission tank 11, as above described. That is to say, the reduction of pressure in the apparatus remains stationary until the valve 22 again admits the compressed air, and the cycle is again repeated.

It is again pointed out that the check valve 46 at the foot of the cylinder 41 prevents any pressure being applied to the liquid in the well proper, so as to maintain the natural flow in the well from the vein undisturbed. The liquid in the apparatus hoisted by the compressed air is instantly replaced by the same volume by the hydrostatic head formed by the liquid in the well and in the apparatus, and with the pressure in the well always normal or atmospheric no matter what pressure is employed in the apparatus.

The valve casing 17 is provided with a fluid passage 20', shown in dotted lines in Fig. 6, so that pressure on both sides of piston valve 22 is balanced.

Having thus described my invention, what I claim as new and desire to secure by Letters Patent is:

1. The combination of a fluid compressor having an admission tank provided with means for adjusting the pressure in said tank not exceeding the atmospheric pressure, and an apparatus of the class described comprising a cylinder, a fluid line, a liquid line, a valve interposed between said fluid line, the exhaust of said compressor and the said admission tank of said compressor, and a check valve associated with said interposed valve whereby the reduction in pressure in said fluid line may be instantly reduced to atmospheric, substantially as described.

2. An apparatus of the class described, comprising a cylinder having a fluid admission and exhaust from the same fluid line at one end and a liquid admission and exhaust at the other end, a valve casing having an admission and exhaust opening for fluid and associated with said fluid line, a cylindrical slide valve inclosed in said casing and having a rod projecting through said casing means on said rod whereby said valve is alternately displaced so as to admit or exhaust the fluid from said fluid line, and a check valve connecting said valve casing on said fluid line with the atmosphere, whereby the pressure in said fluid line, at the moment that the exhaust begins through said valve from said fluid line, falls to the atmospheric pressure, substantially as described.

3. An apparatus of the class described, comprising a cylinder having a fluid admission and exhaust from the same fluid line at one end and a liquid admission and exhaust at the other end, a valve casing having an admission and exhaust opening for fluid and associated with said fluid line, a cylindrical slide valve inclosed in said casing and having a rod projecting through said casing, 5 said rod having a yoke, and a disk having lugs on its opposite faces and adapted to alternately engage said yoke of said rod, one of said lugs being fixed on said disk and the other relatively to the fixed lug is adjustable on the opposite face of said disk, 10 for the purposes above described.
4. An apparatus of the class described, comprising a cylinder having a fluid admission and exhaust from the same fluid line 20 at one end and a liquid admission and exhaust at the other end, a valve casing having an admission and outlet for a fluid and associated with said fluid line, a cylindrical slide valve inclosed in said casing and
- having at one end a rod projecting through 25 the said casing and the other end having an axial bore facing the admission in said casing, said axial bore being provided with an outlet to the surface of said cylindrical valve, thus forming the admission part of 30 said valve, another through bore normal to the axis of said valve and in plane with the surface outlet of said axial bore and at a predetermined distance from said outlet, said bore forming the exhaust part of 35 said valve, and means associated with the said rod of said valve whereby the admission and exhaust parts of said valve are alternately registering the said fluid line with the admission and outlet of said valve 40 casing, substantially as described.

In testimony whereof I have signed my name to this specification in the presence of two subscribing witnesses.

DUNCAN D. McCALL.
